UNITED STATES PATENT OFFICE.

SAMUEL S. JACKSON, OF COLUMBUS, OHIO.

DESIGN FOR AN OVERCOAT, ULSTER, OR A SPORT SACK-COAT.

58,572.

Specification for Design.

Patented Aug. 2, 1921.

Application filed December 30, 1919. Serial No. 348,494. Term of patent 7 years.

To all whom it may concern:

Be it known that I, SAMUEL S. JACKSON, a citizen of the United States, residing at Columbus, in the county of Franklin and State of Ohio, have invented a new, original, and ornamental Design for Overcoats, Ulsters, or Sport Sack-Coats, of which the following is a specification, reference being had to the accompanying drawings, forming part thereof.

Figure 1 is a perspective view of an overcoat or ulster looking toward the front thereof showing my new design.

Fig. 2 is a similar view looking at the back of the garment.

Fig. 3 is a side elevation of the garment showing my new design, the lower part of the coat being broken away.

Fig. 4 is an enlarged detail sectional view of the plait on the line 4—4 Fig. 2, the plaits of the sleeve, back, and front, of the garment being of the same design.

I claim:

The ornamental design for an overcoat, ulster, or a sport sack coat, substantially as shown.

In testimony whereof I affix my signature.

SAMUEL S. JACKSON.
